UNITED STATES PATENT OFFICE.

GEORGE S. CASCADEN, OF PHENIXVILLE, PENNSYLVANIA.

DESIGN FOR A HARNESS ORNAMENT.

SPECIFICATION forming part of Design No. 18,597, dated September 11, 1828.

Application filed March 14, 1828. Serial No. 267,185. Term of patent 14 years.

To all whom it may concern:

Be it known that I, GEORGE S. CASCADEN, a citizen of the United States, residing at Phoenixville, in the county of Chester and State of Pennsylvania, have invented a new and useful Design for Harness Ornaments, of which the following is a specification.

The invention relates to a design for harness ornaments, consisting in a new form and configuration for crown ornaments, terret-rings, &c., which is fully described hereinafter, and specifically pointed out in the appended claim.

The accompanying drawing represents the design.

Referring by letter to the drawing, A represents a square, the apex of which is embedded in the capital of an Ionic column. C and B represent a compass, the legs *b b* of which respectively intersect the arms *a a* of the said square, thus inclosing a space, S, of quadrangular form.

D represents a chain which depends from the joint or pivot portion of the compass, and

to the lower end of the chain is affixed the initial letter G, which is thus arranged about the center of the inclosed space S.

Having thus described the invention, I claim—

The design for harness ornaments herein described and shown, the same consisting of the Ionic column C, the square arranged above the column and having its apex in the capital thereof, the compass having its legs intersecting the arms of the square, the chain extending downward from the joint or pivot portion of the compass, and the initial letter G at the lower end of the chain, substantially as specified.

In testimony that I claim the foregoing as my own I have hereto affixed my signature in presence of two witnesses.

GEO. S. CASCADEN.
